UNITED STATES PATENT OFFICE.

ORIN C. SAMPHERE, OF WEST ALLIS, WISCONSIN.

DENTAL DEVICE.

1,381,750.

Specification of Letters Patent. Patented June 14, 1921.

Application filed May 13, 1920. Serial No. 381,060.

To all whom it may concern:

Be it known that I, ORIN C. SAMPHERE, a citizen of the United States, and resident of West Allis, in the county of Milwaukee and 5 State of Wisconsin, have invented new and useful Improvements in Dental Devices, of which the following is a description, reference being had to the accompanying drawings, which are a part of this specification.

10 The present invention relates to certain new and useful improvements in dental appliances and refers more particularly to what may be generally termed a dental bridge work. 15 The bridge structures now most commonly used in dental work are fixed in the mouth and are undesirable in that particles of food become lodged thereunder and decay and it is impossible to remove the food 20 therefrom.

Numerous removable bridge work structures have been designed to obviate this objection but none of them have satisfied the requirements as they soon become loose and 25 oftentimes are swallowed by the wearer.

Hence with the above and other objections in mind this invention has for one of its objects to provide means for so securing an 30 artificial tooth in place that the same may be readily moved or swung from normal position by the wearer to permit the cleaning of food from therebeneath but at the same time preventing the removal of the artificial tooth from the wearer's mouth.

35 Another object of the present invention is to provide a dental device of the class described in which the artificial teeth are so connected with the natural teeth as to be normally secured in position and, at the same 40 time, capable of being moved from normal position to permit the thorough cleaning of food particles therefrom beneath, the artificial tooth being so secured in place that the same can only be readily removed from 45 the wearer's mouth by a dentist equipped with the proper instruments.

A further object of the present invention is to provide a bridge structure for artificial teeth which may be secured in place without 50 mutilating the adjacent natural teeth and which may be readily removed without destroying, mutilating or in any way interfering with the working of the structure when it is again placed in the mouth.

55 With the above and other objects in view which will appear as the description pro-

ceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing I have 65 illustrated one complete example of the physical embodiment of my invention and a modification thereof constructed according to the best mode I have so far devised for the practical application of the principles 70 thereof, and in which:

Figure 1 is a perspective view of a portion of a jaw and teeth carried thereby illustrating one manner of securing artificial teeth in place by my improved bridge structure.

Fig. 2 is a view looking at the lower edge of the teeth.

Fig. 3 is an enlarged front view thereof, a portion of the attaching member being 80 broken away and in section.

Fig. 4 is a detailed view of the artificial teeth and attaching member removed from the mouth, the artificial teeth being illustrated as moved to a position at substantially 85 180° to its normal position relative to the attaching member;

Fig. 5 is a view part in section and part in elevation taken on the plane indicated by the line 5—5 of Fig. 3;

Fig. 6 is a view similar to Fig. 2 of a modified form of my invention; and

Fig. 7 is a perspective view of that form of my invention depicted in Fig. 6 illustrating artificial teeth as swung from their normal position.

Referring now more particularly to the accompanying drawing the numeral 5 designates the jaw of a person and 6 the natural teeth, and the present invention consists primarily in the means for securing the artificial teeth 7 in position.

In Figs. 1 to 5, inclusive I have illustrated my device as in use in connection with the two rearmost molars connected together by 105 means of the usual artificial gum composition 8 and pivotally connected to a yoke member 9 by means of a pin 10 fixed in one of the teeth 7 and swiveled in the attaching member. The attaching member in the present instance is of substantially U-shape and has arms 11 thereof apertured as at 12 near

their outer ends for engagement over trunnions 13 carried by one of the adjacent fixed teeth 6.

In the present instance I have illustrated 5 the trunnions 13 as carried by a crown 14 secured to the adjacent tooth 6 although it will be readily appreciated that any other desired means may be employed.

The ends 11 of the attaching member are 10 resiliently urged together and are at all times under tension to retain the trunnions 13 in the apertures 12, although the attaching member can readily disengage from the trunnions by springing the arms 11 apart 15 which will in no manner destroy the device.

The teeth 7 are readily releasably secured 20 in normal position by means of a slight hump or projection 15 formed on the crown 14 or other retaining portion for the trunnions 13 over which the portion of the attaching member with which the pin 10 is 25 engaged passes and engages behind as depicted in Fig. 3. As will be obvious but a slight tension is required to retain the parts in normal position.

This structure exposes or presents the entire sides and top of the artificial teeth to facilitate a thorough brushing without removing from the mouth, but when it is desired to clean from beneath the artificial teeth they are raised to the position depicted 30 in Fig. 3 and may be moved on the swivel or pivot 10 as depicted in Fig. 4 to permit the better and more thorough cleaning 35 thereof.

In Figs. 6 and 7 I have illustrated a slightly modified form of my invention in which one or more artificial teeth are secured 40 between natural teeth, in which instance the artificial teeth are secured upon a base 16 one end of which carries the attaching member 9 and the other end of which has an interlocking projection 17 adapted to engage within a recess 18 formed in a 45 gold filling 19 of the adjacent natural tooth 6'. The portion of the foundation 16 adjacent the attaching member 9 may also be provided with a projection 20 for engagement 50 in a recess 21 formed within the crown 14' to which the attaching member 9 is secured.

In this form of my device, the artificial teeth may be releasably retained in normal position by means of two spring arms 22 carried 55 by the foundation and adapted to bind against the adjacent tooth 6' as thus shown in Fig. 6. As in the other form of my in-

vention, the arms 11 of the attaching member may be sprung apart to disengage the trunnions 13 and permit the complete removal of the artificial teeth from the mouth, and if desired the interlocking projection 17 and 60 20 may be dispensed with as may be readily apparent to those skilled in the art to which an invention of this character ap- 65 pertains.

What I claim as my invention is:

1. A dental device for attaching a movable tooth to a fixed tooth consisting of a means 70 forming a pivotal and a swivel connection between the two teeth.

2. In a dental device, the combination with a fixed tooth and a movable tooth, of an attaching member having a pivotal connection with the fixed tooth and a swivel connection 75 with the movable tooth.

3. A dental device comprising an attaching member, a swivel connection between said member and an artificial tooth, means 80 pivotally connecting the attaching member with a fixed tooth, and means releasably securing the artificial tooth in normal position.

4. In a dental device, the combination with a fixed tooth and a removable tooth, of a 85 yoke member, means pivotally connecting the ends of the arms of the yoke member with the fixed tooth, and a swivel connection between the closed end of the yoke and the removable tooth.

5. In a dental device, the combination with a removable tooth, a fixed tooth and a laterally projecting trunnion carried by one of the teeth, of an attaching member 95 having one end apertured and engaged with said trunnion to provide a pivotal connection between said member and the tooth carrying said trunnion, and a swivel connection between the other end of said member and the other tooth.

6. In a dental device, the combination with a fixed tooth and a removable tooth, of an attaching member carried by said removable tooth, a pivotal connection between said member and the fixed tooth, and means for 105 releasably securing the removable tooth against movement on its pivot including a hump formed on said fixed tooth and over which said attaching member must spring when the removable tooth is moved to its 110 normal position.

In testimony whereof, I affix my signature.

ORIN C. SAMPHERE.
